[57] **CLAIM**

The ornamental design for a fist air freshener, as shown and described.

DESCRIPTION

FIG. 1 is a top perspective view of a first embodiment of the fist air freshener of our design;

FIG. 2 is a bottom perspective view thereof;

FIG. 3 is a front view thereof;

FIG. 4 is a rear view thereof;

FIG. 5 is a side view thereof;

FIG. 6 is an opposing side view thereof;

FIG. 7 is a top perspective view of a second embodiment of the fist air freshener of our design; and,

FIG. 8 is a top perspective view of a third embodiment of the fist air freshener of our design.

The sole difference from the first embodiment resides in the appearance of the rings; a smaller number in the second embodiment, and the lack of rings in the third embodiment.
